(57) **CLAIM**

An ornamental design for a bracket, as shown and described.

DESCRIPTION

FIG. 1 is a perspective view of a bracket;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The evenly spaced broken lines shown in the drawings illustrate portions of the bracket that form no part of the claimed design. The dash-dot-dash broken lines shown in the drawings depict the boundary of the claim and form no part of the claimed design.

1 Claim, 4 Drawing Sheets
